(57) CLAIM

The ornamental design for a desk pen holder and tape dispenser, as shown and described.

DESCRIPTION

FIG. 1 is a front top side perspective view of my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a back elevational view thereof; and,

FIG. 7 is a bottom plan view thereof.

The broken lines shown in the drawings depict environmental matter and form no part of the claimed design, except for the broken lines outlining the large, central compartment and the tape dispensing compartment in FIG. 2, both of which define the bounds of the claimed design and form no part thereof.
